UNITED STATES PATENT OFFICE

CARRIE BABBITT, OF BROOKLYN, NEW YORK

DESIGN FOR A COMBINED SEWING IMPLEMENT AND PIN HOLDER

Application filed April 6, 1931. Serial No. 39,385. Term of patent 7 years.

To all whom it may concern:

Be it known that I, CARRIE BABBITT, a citizen of the United States, residing in the borough of Brooklyn, New York city, in the county of Kings and State of New York, have invented a new, original, and ornamental Design for a Combined Sewing Implement and Pin Holder, of which the following is a specification, reference being had to the accompanying drawings, forming part thereof.

Fig. 1 is a front elevational view of a combined sewing implement and pin holder, showing my new design.

Fig. 2 is a side elevational view of the same.

Fig. 3 is a rear elevational view of the same.

I claim:

The ornamental design for a combined sewing implement and pin holder, as shown.

In testimony whereof I have affixed my signature.

CARRIE BABBITT.
